UNITED STATES PATENT OFFICE.

ALPHONSE GUTTLY, OF WISCONSIN RAPIDS, WISCONSIN.

WRENCH.

Application filed September 6, 1921. Serial No. 498,817.

To all whom it may concern:

Be it known that I, ALPHONSE GUTTLY, a citizen of Switzerland, residing at Wisconsin Rapids, in the county of Wood and State 5 of Wisconsin, have invented new and useful Improvements in Wrenches, of which the following is a specification.

My present invention has reference to improvements in wrenches.

10 My object is to produce a quick acting wrench in which the slideable jaw, by a pressure of the thumb or the finger of the operator thereon may be brought out of engagement with the shank of the stationary jaw 15 and rapidly moved toward or away from said jaw, said slideable jaw being also provided with a screw which engages with the teeth of the shank of the stationary jaw, whereby a minute adjustment between the 20 jaws may be obtained for accurately engaging an object therebetween.

A further object is to produce a wrench in which all of the parts constituting the same shall be of a simple construction and 25 shall be interchangeable as well as easily assembled either when arranging the elements to provide a complete wrench or when repairs are required in parts of the wrench.

The foregoing, and other objects which 30 will appear as the nature of the invention is better understood, may be accomplished by a construction, combination and operative association of parts, such as is disclosed by the drawings which accompany and which 35 form part of this specification.

In the drawings:—

Figure 1 is a side elevation of a wrench in accordance with this invention.

Figure 2 is a top plan view thereof.

40 Figure 3 is a sectional view on the line 3—3 of Figure 1.

Figure 4 is a sectional view on the line 4—4 of Figure 1.

Figures 5 and 6 illustrate details.

45 The stationary jaw 1 of my improved wrench is integrally formed with an angle shank 2, and the said shank may have its free end beveled to provide an instrument to engage in the kerfs of screws or for other 50 purposes. Also, the shank, adjacent to its free end is preferably provided with an opening whereby the wrench may be suspended from a nail or the like when not in use. The sides of the shank are grooved 55 longitudinally, and one of the edges thereof is provided with curved or arcuate teeth 3

formed by depressing the said edge of the shank.

The movable jaw includes a carriage 4 carrying a head or jaw 5 and freely movable 60 over the shank 2. The carriage, at the center thereof has its top and its sides reduced or provided with grooves 6 respectively, while the said shank is also provided with a slot or opening in a line with the said 65 grooves and which enter the bore of the shank. This slot or opening is indicated by the numeral 7.

Received in the grooves or sides of the shanks are plates 8. These plates are connected at one of their ends by reduced portions 9, the said reduced portions being received in a slot or opening 7 and being formed with bearing openings for a shaft 10 on which is journaled a screw 11, the said 75 screw designed to engage with the teeth of the shank 2. The groove in the top or upper portion of the shank or carriage 4 is centrally provided with a depression 12 in which is seated a spring 13. The plates 8 have 80 their confronting sides, which are disposed opposite the said groove, channeled, as at 4, and in these channels or grooves 14 there is received the reduced edges or tongues 15 formed on a plate 16. The plate 16 contacts with the spring, so that the spring 85 exerts a pressure thereagainst, and moves the yoke provided by the plates 8 in a direction to bring the screw 11 to engage with the teeth of the shank 2. The outer surface 90 of the plate 16 is preferably rounded and is milled, as at 17, whereby the operator may 95 freely engage the same to exert a downward pressure thereagainst to move the yoke to bring the screw out of engagement with the teeth of the shank to cause the carriage to be moved longitudinally in either direction 100 on the shank 1, thus bringing the jaw 5 toward or away from the jaw 1. The outer periphery of the screw is preferably milled 105 so that the same can be easily turned when a minute adjustment is required between the jaws 1 and 5, and it is thought that the foregoing description, when taken in connection with the drawings will fully set forth the 110 construction and advantages of the improvement so that further description is not considered necessary.

Having thus described the invention, what is claimed as new, is:—

A wrench including a jaw having a toothed shank, a carriage slideable on the

shank and provided with a jaw, said carriage having aligning grooves in its sides and top and its lower edge notched in alignment with the grooves, said carriage being also provided with a depression in the grooved portion of its top, a yoke having its arms mounted within the grooves of the sides and extending beyond the top of the carriage, said arms being provided with channels in their opposite faces near their

outer ends, a screw mounted in the bottom of the yoke within the notch in the carriage, a plate mounted in the channels of the arms and provided with a recess opposite that in the top of the carriage, and a coil spring mounted between said plate and carriage having an end seated in each recess. 15

In testimony whereof I affix my signature.

ALPHONSE GUTTLY.
